ABSTRACT

A random access type semiconductor memory comprises a pair of data line halves arranged in parallel, a plurality of word lines orthogonal to the data line halves, a multiplicity of memory cells, each of which is arranged at either one of the cross points between the data line halves and each of the word lines, a differential amplifier to which signals on the data line halves are differentially applied, and a main amplifier to which output signals on the data line halves are differentially applied, thereby detecting the content of a desired memory cell.

SEMICONDUCTOR MEMORY

Matter enclosed in heavy brackets [ ] appears in the original patent but forms no part of this reissue specification; matter printed in italics indicates the additions made by reissue.

BACKGROUND OF THE INVENTION

1. Field of the Invention

This invention relates to a random access type memory arrangement for a semiconductor memory.

2. Description of the Prior Art

In a prior art random access type semiconductor memory, a data line is divided into two halves, each of which has a plurality of memory cells and a dummy cell, and a differential amplifier is connected between the left half and the right half of the data line. The contents of a desired memory cell connected to one data line half are read out and, at the same time, the contents of a dummy cell connected to the other data line half are also read out. The voltage on either one of the data line halves is detected through a switching element.

However, such a prior art memory has the following disadvantages.

Since only the voltage on one of the digit line halves is detected, it is impossible to read out the data at a high speed and there is the possibility of erroneously detecting the contents of a memory cell due to an electrical imbalance of the data line halves.

Since the data line halves are not geometrically adjacent each other, unbalanced noise signals are produced on the data line halves, thereby causing the differential amplifier to operate erroneously.

SUMMARY OF THE INVENTION

An object of the invention is to provide a random access type semiconductor memory which can operate at a high speed and at a stable condition.

In order to attain such an object, this invention is characterized by arranging the data line halves so as to be adjacent each other.

BRIEF DESCRIPTION OF THE DRAWINGS

FIG. 1 is a diagram showing part of a circuit construction of a prior art memory.

FIG. 2 is a diagram showing the entire circuit construction of a prior art memory.

FIG. 3 is a diagram showing an embodiment of a semiconductor memory according to this invention.

FIGS. 4a to 4c are diagrams showing various embodiments of a memory cell arrangement according to this invention.

FIGS. 5a and 5b are respective plane and sectional views showing an embodiment of memory arrangement according to this invention.

FIG. 6 is a plane view showing another embodiment of memory arrangement according to this invention.

DETAILED DESCRIPTION OF THE PRIOR ART

At least one memory cell MC₀ and a dummy memory cell DM₀ are connected to the left half D₀ of a data line and at least one memory cell MC₁ and a dummy memory cell DM₁ are connected to the right half D̄₀ of a data line. These data line halves D₀ and D̄₀ are connected to a pre-amplifier PA₀ using a differential amplifier.

Each of the memory cells MC₀, MC₁, DM₀ and DM₁ comprises a MOS (metal-oxide-semiconductor) transis-

tor Q and a capacitor C₀. The gates of the MOS transistors Q in the memory cells MC₀ and DM₀ are connected to word lines W₀ and DW₀ which are orthogonal to data line half D₀. The gates of the MOS transistors Q in memory cells MC₁ and DM₁ are connected to word lines W₁ and DW₁ which are orthogonal to data line half D̄₀. The drains of MOS transistors Q in memory cells MC₀, DM₀ and CM₀, DM₁ are connected to data line halves D₀ and D̄₀, respectively. The capacitors C₀ in the respective memory cells are connected between the sources of the respective transistors Q and ground.

The preamplifier PA₀ has a pair of cross-coupled MOS transistors Q_{P1} and Q_{P2} connected between the data line halves D₀ and D̄₀ and MOS transistors Q_{P3} to Q_{P5}. The drains and gates of MOS transistors Q_{P3} and Q_{P4} are connected to a power supply terminal V_{DD} and a set signal terminal S₁, respectively, and the sources thereof are connected to the drains of MOS transistors Q_{P1} and Q_{P2}. The gate and source of MOS transistor Q_{P5} are connected to a set signal terminal S₂ and ground, respectively, and the drain thereof is connected to the sources of MOS transistors Q_{P1} and Q_{P2}.

In operation, where the contents of memory cell MC₀ connected to data line half D₀ are read out, pulses are applied to the corresponding work line W₀ and dummy word line DW₁ orthogonal to data line half D̄₀. Small signals on the data line halves D₀ and D̄₀ which have different values with respect to each other are applied to the pre-amplifier PA₀. The small signals are amplified by the pre-amplifier PA₀ when the set signal is applied to terminals S₁ and S₂.

Furthermore, an amplified signal on one of the data line halves D₀ and D̄₀ is detected, thereby detecting the information ("1" or "0") of a desired memory cell MC₀.

In detail, the voltage across capacitor C₀ in dummy cell DM₁ is a voltage intermediate an information "1" voltage and an information "0" voltage across capacitor C₀ in memory cell MC₀. Therefore, signal read out from dummy cell DM₁ to data line half D̄₀ has a value intermediate information "1" and "0" signals read out from memory cell MC₁ to data line half D₀. Output signals which are of different polarities with respect to each other are obtained by the pre-amplifier PA₀ in response to the difference between signals on the data line halves D₀ and D̄₀.

FIG. 2 shows a circuit of a large scale integrated (LSI) memory which employs the random access type memory circuit shown in FIG. 1.

In FIG. 2, MC₀ to MC₆₃ represent memory cells, DM₀ and DM₁ dummy cells, W₀ to W₆₃ and DW₀ and DW₁ word lines, D₀ to D₆₃ and D̄₀ to D̄₆₃ data line halves, A₀ to A₆₃ address signal terminals, MA a main amplifier, T₀ an output terminal, Q₀ to Q₆₃ MOS transistors and WD a word driving circuit.

In order to detect signals on data line halves D₀ to D₆₃, address signals A₀ to A₆₃ are selectively applied to the gates of MOS transistors Q₀ to Q₆₃. For example, when a signal on data line half D₀ is detected, MOS transistor Q₀ is made conductive by a signal from terminal A₀. Therefore, a signal on data line half D₀ is applied to the main amplifier MA and an amplified signal is derived from the output terminal T₀.

The contents of the memory cells MC₀ to MC₆₃ are read out by word signals on the word lines W₀ to W₆₃. At the same time, the contents of dummy cell DM₀ or DM₁ are read out by a word signal on word line DW₀ or DW₁. These word signals are supplied from the

word driving circuit WD. For example, when the information stored in memory cell MC₆₂ is read out, word signals are applied to word lines W₆₂ and DW₁.

The prior art memory shown in FIGS. 1 and 2 has the following disadvantages.

1. Since only a signal on either one of data line halves D₀ and $\bar{D}_0$ is amplified by the main amplifier MA, it is impossible to detect the contents of a desired memory cell at a high speed.

2. There is the possibility of erroneously detecting the contents of a desired memory cell by an electrical imbalance of data line halves D₀ and $\bar{D}_0$.

3. Since the data line halves D₀ and $\bar{D}_0$ are geometrically separated from each other, unbalanced noise signals are produced on the data line halves D₀ and $\bar{D}_0$. Therefore, there is the possibility that the pre-amplifier PA₀ will operate erroneously.

DETAILED DESCRIPTION OF THE INVENTION

FIG. 3 shows an embodiment of circuit construction of a semiconductor memory random access type according to this invention.

In FIG. 3, a pair of data line halves D₀ and $\bar{D}_0$ are arranged at adjacent positions and in parallel.

Each of the memory cells MC₀ to MC₆₃ is connected between one of the word lines W₀ to W₆₃ which are orthogonal to the data line halves D₀ and $\bar{D}_0$ and one of the data line halves D₀ and $\bar{D}_0$. That is, a memory cell is connected to only one of the cross points between each of the word lines W₀ to W₆₃ and the data line halves. Memory cells MC₁ to MC₆₂ (even number) are connected between word lines W₀ to W₆₂ (even number) and data line half $\bar{D}_0$ and memory cell MC₁ to MC₆₃ (odd number) are connected between word lines W₁ to W₆₃ (odd number) and data line half D₀. Furthermore, a dummy memory cell DM₀ is connected between a word line DW₀ and data line half $\bar{D}_0$ and a dummy memory cell DM₁ is connected between a word line DW₁ and data line half D₀. The data line halves D₀ and $\bar{D}_0$ are connected to a pre-amplifier, such as PA₀ shown in FIG. 1 and are further connected to the main amplifier MA through MOS transistors Q₀ and $\bar{Q}_0$, respectively. An address signal from terminal A₀ is applied to MOS transistors Q₀ and $\bar{Q}_0$.

Signals on other data line halves connected in common to common data lines CD and $\bar{CD}$ are also applied to the main amplifier MA.

When the contents of a desired memory cell, for example, MC₆₃, are read out, word signals are applied to memory cell MC₆₃ and dummy cell DM₀ which is connected to data line half $\bar{D}_0$. Signals on the data line halves D₀ and $\bar{D}_0$ are applied to the pre-amplifier PA₀. Signals amplified differentially by the pre-amplifier PA₀ are applied through transistors Q₀ and $\bar{Q}_0$ to the main amplifier MA using a differential amplifier at the application of the address signal from terminal A₀. A signal amplified differentially by the main amplifier MA is derived from the output terminal T₀.

Since a pair of data line halves D₀ and $\bar{D}_0$ are arranged in parallel and both signals on the data line halves D₀ and $\bar{D}_0$ are applied through MOS transistors Q₀ and $\bar{Q}_0$ to the main amplifier MA, it is possible to maintain an electrical balance of the data line halves D₀ and $\bar{D}_0$.

FIGS. 4a to 4c show various embodiments of a random access type memory cell arrangement according to this invention.

In these figures, a circle represents the presence of a memory cell and an X represents the absence of a memory cell. Memory cells are arranged alternately one by one on the data line halves D₀ and $\bar{D}_0$ in FIG. 4a. Memory cells are arranged alternately in pairs on the data line halves D₀ and $\bar{D}_0$ in FIG. 4b. Furthermore, memory cells are arranged alternately in fours on the data line halves D₀ and $\bar{D}_0$ in FIG. 4c.

FIG. 5a shows a plane view of an embodiment of a random access type memory arrangement according to the invention for realizing the memory arrangement shown in FIG. 4b by means of a silicon gate.

FIG. 5b shows a sectional view along line Vb-Vb' in FIG. 5a. In these figures, CP represents a storage capacitor forming electrode for forming storage capacitors C₀ in the memory cells. 400 and 410 represent the drain and source (or source and drain) of transistor Q shown in FIG. 1, which are formed in a silicon substrate 600.

100 represents a contact part between the data line halves D₀, D₀, etc., and a diffusion layer 400 forming a drain (or source). 200 represents an insulating layer for separating word line W₅₉ from data line half D₁.

20 Electrodes CP and word lines W₅₈, W₅₉, etc. are formed of polysilicon and data line halves D₀, $\bar{D}_0$, etc. are formed of aluminum.

In a N-channel MOS, the storage capacitor C₀ is formed between a channel 500 and an electrode CP when a high voltage is applied to the electrode CP.

In such an arrangement, when pulse voltages are applied to a word line, for example, W₆₀, transistor Q comprising drain 400 and source 410 connected to the cross point between word line W₆₀ and data line half D₀ is made conductive. Therefore, the storing voltage of the storage capacitor C₀ beneath the data line half D₀ is read out so that this voltage is divided by the capacitance of the data line half D₀ and the storage capacitor C₀. The storing voltage of the storage capacitor C₀ beneath the data line half $\bar{D}_0$ is not read out, since there is no transistor connected to the cross point between word line W₆₀ and data line half $\bar{D}_0$. The voltage from a dummy cell (not shown in the figure) is present on data line half $\bar{D}_0$.

FIG. 6 shows a plane view of another embodiment of a random access type memory arrangement according to this invention for realizing the memory arrangement in FIG. 4c by means of a silicon gate.

Since the construction and operation of a random access type memory arrangement shown in FIG. 6 are similar to those of memory arrangement shown in FIG. 5a except that memory cells are arranged alternately four by four on the data line halves D₀ and $\bar{D}_0$, a detailed description thereof will be omitted.

In these embodiments, it is also possible to use aluminum in lieu of polysilicon as the word lines.

According to the memory arrangement of the invention shown in FIGS. 3 and 4, the following advantages are obtained.

1. Since both signals on the data line halves D₀ and $\bar{D}_0$ are differentially applied through MOS transistors Q₀ and $\bar{Q}_0$ to the main amplifier, it is possible to detect the contents of a desired memory cell at a high speed.

2. Since there is no electrical imbalance of the data line halves D₀ and $\bar{D}_0$, the contents of a desired memory cell are correctly detected.

3. Since the data line halves D₀ and $\bar{D}_0$ are geometrically adjacent each other, no imbalance noise signals are produced on the data line halves D₀ and $\bar{D}_0$. Therefore, the pre-amplifier MA operates correctly.

4. In the prior art memory shown in FIGS. 1 and 2, the pre-amplifier PA₀, which has an area far greater than that of a memory cell, must be arranged between the data line halves D₀ and $\bar{D}_0$. Therefore, it is difficult to arrange such a pre-amplifier so as to maintain a desired pitch of a data line. However, in a memory of the invention shown in FIG. 3, since a pair of data line halves D₀ and $\bar{D}_0$ are arranged in parallel on one side of pre-amplifier PA₀, such a pre-amplifier can be arranged so as to maintain a desired pitch of a data line.

In FIG. 3, the pre-amplifier PA₀ may be arranged between MOS transistors Q₀ and $\bar{Q}_0$ and the main amplifier MA. Furthermore, it can be arranged on the left terminal side, that is, the word line W₆₃ side. In such a case, it is possible to obviate the concentration of the control circuits (PA₀, Q₀, etc.), which arrangement is relatively difficult, on one side.

If necessary, the pre-amplifiers, which are provided for every pair of data line halves, may be arranged alternately on one side and the other sides.

Thus, it is possible to remarkably increase the freedom of the memory arrangement.

In FIG. 3, various differential amplifiers can be used as the pre-amplifier PA₀. Each of the memory cells MC₀ to MC₆₃, DM₀ and DM₁ can be constituted by a memory cell of various types in lieu of a circuit shown in FIG. 1.

Furthermore, according to the invention, dummy memory cells DM₀ and DM₁ can be eliminated since the data line halves D₀ and $\bar{D}_0$ are arranged in parallel.

I claim:

1. A semiconductor memory comprising:
at least a pair of data line portions arranged in parallel with each other and at positions adjacent to each other;
a plurality of first word lines orthogonally crossing over said data line portions;
a multiplicity of memory cells, each of which is coupled to a respective data line portion and a respective first word line at the cross point thereof and can perform random access for write-in and read-out of data;
a differential amplifier to which signals on said pair of data line portions are respectively applied; [and] means, connected to said differential amplifier and said data line portions, for deriving output signals representative of signals on said pair of data line portions [.]
a pair of second word lines orthogonally crossing over said data line portions;
a first dummy memory cell coupled to one of the data line portions of said pair of data line portions and one of said second word lines at the cross point thereof; and
a second dummy memory cell coupled to the other of the data line portions of said pair of data line portions and the other of said second word lines at the cross point thereof, wherein deriving signals are applied to one of said first word line and one of said pair of second word lines at the same time, so that data from one of said multiplicity of memory cells and one of said dummy memory cells are, respectively, read out on one and the other of said pair data line portions, at the same time.

[2. A semiconductor memory according to claim 1, further comprising,

- a pair of second word lines orthogonally crossing over said data line portions;

a first dummy memory cell coupled to one of the data line portions of said pair of data line portions and one of said second word lines at the cross point thereof, and

a second dummy memory cell coupled to the other of the data line portions of said pair of data line portions and the other of said second word lines at the cross point thereof.]

[3. A semiconductor memory according to claim 1, wherein said output signal deriving means comprises a pair of switching elements connected to said data line portions and a second differential amplifier connected to said pair of switching elements, to which the signals on said data line portions are selectively applied through said pair of switching elements.]

4. A semiconductor memory according to claim 3, wherein said switching elements comprise a pair of transistors, each having an input terminal connected to a respective data line portion, an output terminal connected to said second differential amplifier, and a control terminal to which a control signal is applied.

[5. A semiconductor memory according to claim 1, wherein each of said memory cells comprises a metal-oxide-semiconductor transistor and a storage capacitor connected therewith.]

[6. A semiconductor memory according to claim 1, wherein, for each of said data line portions, the memory cells coupled thereto are coupled, alternately, to every other word line.]

[7. A semiconductor memory according to claim 1, wherein, for each of said data line portions, the memory cells coupled thereto are coupled in alternate pairs of adjacent word lines.]

[8. A semiconductor memory according to claim 1, wherein for each of said data line portions, the memory cells coupled thereto are coupled in alternate groups of four of adjacent word lines.]

[9. A semiconductor memory according to claim 1, wherein said memory cells are coupled to said data line portions and said word lines so that the electrical characteristics of said data line portions are balanced with respect to each other.]

[10. A semiconductor memory according to claim 1, wherein the number of memory cells connected to one of the data line portions of said pair of data line portions is equal to the number of memory cells connected to the other of the data line portions of said pair of data line portions.]

[11. A semiconductor memory according to claim [3] 2, further comprising

- a pair of second word lines orthogonally crossing over said data line portions;
- a first dummy memory cell coupled to one of the data line portions of said pair of data line portions and one of said second word lines at the cross point thereof; and
- a second dummy memory cell coupled to the other of the data line portions of said pair of data line portions and the other of said second word lines at the cross point thereof.

[12. A semiconductor memory according to claim 11, wherein said switching elements comprise a pair of transistors, each having an input terminal connected to a respective data line portion, an output terminal connected to said second differential amplifier, and a control terminal to which a control signal is applied.

【13. A semiconductor memory according to claim 1, wherein said data line portions are formed of aluminum and said first word lines are formed of polysilicon.】

14. A random access semiconductor memory comprising:

first and second data line portions disposed parallel and adjacent to each other;
a plurality of first word lines orthogonally crossing over each of said data line portions;
a plurality of memory cells, disposed at the cross points of said first word lines and one of said data line portions, each of which memory cells is capable of storing selected information to be written therein and is capable of reading out information stored therein, each memory cell having an address terminal connected to a respective word line so that each word line is connected to the address terminal of only one memory cell, and having a data terminal connected to one of said data line portions;
a differential amplifier connected to each of said data line portions for differentially amplifying signals supplied thereby;
means, connected to said differential amplifier and said data line portions; for deriving output signals representative of signals on said pair of data line portions;
a pair of second word lines orthogonally crossing over each of said data line portions;
a first dummy memory cell, disposed at the crosspoint of one of said second word lines and said first data line, and being capable of storing selected information to be written therein, and being capable of reading out information stored therein, and having an address terminal connected to said one of said second word lines, and having a data terminal connected to said first data line portion; and
a second dummy memory cell, disposed at the cross-point of the other of said second word lines and said second data line, and being capable of storing selected information to be written therein, and being capable of reading out information stored therein, and having an address terminal connected to said other of said second word lines, and having a data terminal connected to said second data line portion, wherein driving signals are applied to one of said first word lines and one of said second word lines, at the same time, so that data from one of said plurality of memory cells and one of said dummy memory cells are, respectively read out on one and the other of said data line portions, at the same time.

【15. A random access semiconductor memory according to claim 14, wherein said output signal deriving means comprises

a pair of switching elements connected to said data line portions and
a second differential amplifier connected to said pair of switching elements, to which the signals on said data line portions are selectively applied through said pair of switching elements.】

16. A semiconductor memory according to claim 15, wherein each of said memory cells comprises a metal-oxide-semiconductor transistor and a storage capacitor connected therewith.

17. A semiconductor memory according to claim 16, wherein said switching elements comprise a pair of transistors, each having an input terminal connected to a respective data line portion, an output terminal con-

nected to said second differential amplifier, and a control terminal to which a control signal is applied.

18. A semiconductor memory comprising:

at least a pair of data line portions arranged in parallel with each other and at positions adjacent to each other;
a plurality of first word lines orthogonally crossing over said data line portions;
a multiplicity of memory cells, each of which is coupled to a respective data line portion and a respective first word line at the cross point thereof and can perform random access for write-in and read-out of data;
a first differential amplifier to which signals on said pair of data line portions are respectively applied;
means, connected to said first differential amplifier and said data line portions, for deriving output signals representative of signals on said pair of data line portions and said output signal deriving means having:
a pair of switching elements connected to said data line portions; and
a second differential amplifier connected to said pair of switching elements, to which the signals on said data line portions are selectively applied through said pair of switching elements.

19. A semiconductor memory comprising:

at least a pair of data line portions formed of aluminum arranged in parallel with each other and at positions adjacent to each other;
a plurality of first word lines formed of polysilicon orthogonally crossing over said data line portions;
a multiplicity of memory cells, each of which is coupled to a respective data line portion and a respective first word line at the cross point thereof and can perform random access for write-in and read-out of data;
a differential amplifier to which signals on said pair of data line portions are respectively applied; and
means, connected to said differential amplifier and said data line portions, for deriving output signals representative of signals on said pair of data line portions.

20. A semiconductor memory comprising:

at least a pair of data line portions arranged in parallel with each other and at positions adjacent to each other;
a plurality of first word lines orthogonally crossing over said data line portions;
a multiplicity of memory cells, each of which is coupled to a respective data line portion and a respective first word line at the cross point thereof and can perform random access for write-in and read-out of data, said memory cells coupled such that pairs of cells coupled to adjacent word lines are alternately coupled to one and the other of said pair of data lines;
a differential amplifier to which signals on said pair of data line portions are respectively applied; and
means, connected to said differential amplifier and said data line portions, for deriving output signals representative of signals on said pair of data line portions.

21. A semiconductor memory comprising:

at least a pair of data line portions arranged in parallel with each other and at positions adjacent to each other;
a plurality of first word lines orthogonally crossing over said data line portions;
a multiplicity of memory cells, each of which is coupled to a respective data line portion and a respective first word line at the cross point thereof and can perform random access for write-in and read-out of data, the memory cells of said data line portions, said memory

cells coupled such that groups of four cells coupled to four adjacent word lines are alternately coupled to one and the other of said pair of data lines;

a differential amplifier to which signals on said pair of data line portions are respectively applied; and 5 means, connected to said differential amplifier and said data line portions, for deriving output signals representative of signals on said pair of data line portions.

22. A semiconductor memory comprising:

at least two pairs of data line portions arranged in parallel with each other and at positions adjacent to each other; 10

a plurality of first word lines orthogonally crossing over said data line portions;

a multiplicity of memory cells, each of which is coupled to a respective data line portion and a respective first word line at the cross point thereof and can perform random access for write-in and read-out of data; 15

first and second differential amplifiers to which signals on said two pairs of data line portions are respectively applied, one of said differential amplifiers connected to one side of an arrangement formed by said data line portions and the other differential amplifier connected to the other side thereof; and 20

means, connected to said differential amplifier and said data line portions, for deriving output signals representative of signals on said pair of data line portions. 25

23. A semiconductor memory comprising:

at least a pair of data line portions arranged in parallel with each other and at positions adjacent to each other; 30

a plurality of first word lines orthogonally crossing over said data line portions;

a multiplicity of memory cells, each of which is coupled to a respective data line portion and a respective first word line at the cross point thereof and can perform random access for write-in and read-out of data, the memory cells of said data line portions, said memory cells coupled such that pairs of cells coupled to adjacent word lines are alternately coupled to one and the other of said pair of data lines; 35

a differential amplifier to which signals on said pair of data line portions are respectively applied; and

each of said memory cells being a metal-oxide semiconductor transistor having an input electrode, an output electrode and a gate electrode, the respective output electrodes of two MOS transistors in two adjacent memory cells being connected at the same location to one data line portion and the respective gate electrodes thereof being connected to two respective adjacent word lines. 40

24. A semiconductor memory comprising:

at least a pair of data line portions arranged in parallel with each other and at positions adjacent to each other; 45

a plurality of first word lines orthogonally crossing over said data line portions;

a multiplicity of memory cells, each of which is coupled to a respective data line portion and a respective first word line at the cross point thereof and can perform random access for write-in and read-out of data; 50

a differential amplifier to which signals on said pair of data line portions are respectively applied;

means, connected to said differential amplifier and said data line portions, for deriving output signals representative of signals on said pair of data line portions; and 55

10

each of said memory cells comprising a metal-oxide semiconductor transistor with source drain and gate regions, the direction of the channel formed between the source and drain regions of said MOS transistor being parallel to the direction of said data line portions.

25. A semiconductor memory comprising:

at least a pair of data line portions arranged in parallel with each other and at positions adjacent to each other;

a plurality of first word lines orthogonally crossing over said data line portions;

a multiplicity of memory cells, each of which is coupled to a respective data line portion and a respective first word line at the cross point thereof and can perform random access for write-in and read-out of data;

a differential amplifier to which signals on said pair of data line portions are respectively applied;

means, connected to said differential amplifier and said data line portions, for deriving output signals representative of signals on said pair of data line portions; and

each of said memory cells comprising a metal-oxide-semiconductor transistor having a gate electrode with the gate electrode of said MOS transistor in each memory cell formed by a portion of one of said first word lines.

26. A semiconductor memory comprising:

at least a pair of data line portions arranged in parallel with each other and at positions adjacent to each other; 30

a plurality of first word lines orthogonally crossing over said data line portions;

a multiplicity of memory cells, formed at said surface, each of which is coupled to a respective data line portion and a respective first word line at the cross point thereof and can perform random access for write-in and read-out of data;

a differential amplifier to which signals on said pair of data line portions are respectively applied;

means, connected to said differential amplifier and said data line portions, for deriving output signals representative of signals on said pair of data line portions; said output signal deriving means comprising a pair of switching elements connected to said data line portions and a pair of common data lines connected to said pair of switching elements.

27. A random access semiconductor memory comprising:

first and second data line portions disposed parallel and adjacent to each other;

a plurality of first word lines orthogonally crossing over each of said data line portions;

a plurality of memory cells, disposed at the cross points of said first word lines and one of said data line portions, each of which memory cells is capable of storing selected information to be written therein and is capable of reading out information stored therein, each memory cell having an address terminal connected to a respective word line so that each word line is connected to the address terminal of only one memory cell, and having a data terminal connected to one of said data line portions;

a differential amplifier connected to each of said data line portions for differentially amplifying signals supplied thereby;

means, connected to said differential amplifier and said data line portions for deriving output signals represen-

tative of signals on said pair of data line portions comprising:
 a pair of switching elements connected to said data line portions, and
 a second differential amplifier connected to said pair of switching elements, to which the signals on said data line portions are selectively amplified through said pair of switching elements;
 a pair of second word lines orthogonally crossing over each of said data line portions;
 a first dummy memory cell, disposed at the crosspoint of one of said second word lines and said first data line, and being capable of storing selected information to be written therein, and being capable of reading out information stored therein and having an address terminal connected to said one of said second word lines, and having a data terminal connected to said first data line portion; and
 a second dummy memory cell, disposed at the crosspoint of the other of said second word lines and said second data line, and being capable of storing selected information to be written therein, and being capable of reading out information stored therein, and having an address terminal connected to said other of said second word lines, and having a data terminal connected to said second data line portion.

28. A semiconductor memory comprising:
 at least a pair of data line portions formed of aluminum arranged in parallel with each other and at positions adjacent to each other;
 a plurality of first word lines formed of polysilicon orthogonally crossing over said data line portions;
 a multiplicity of memory cells, each of which is coupled to a respective data line portion and a respective first word line at the cross point thereof and can perform random access for write-in and read-out of data for each of said data line portions, said memory cells coupled such that pairs of cells coupled to adjacent word lines are alternately coupled to one and the other of said pair of data lines;
 a differential amplifier to which signals on said pair of data line portions are respectively applied;
 means, connected to said differential amplifier and said data line portions, for deriving output signals representative of signals on said pair of data line portions.

29. A semiconductor memory according to claim 22, wherein said differential amplifiers are arranged alternately on one side and the other side of the arrangement formed by said pairs of data line portions.

30. A semiconductor memory according to claim 24, wherein said data line portion overlaps said channel as viewed in the vertical direction.

31. A semiconductor memory according to claim 1, wherein said pair of second word lines are arranged at positions adjacent to each other.

32. A semiconductor memory according to claim 18, wherein, for each of said data line portions, the memory cells coupled thereto are coupled in alternate pairs of adjacent word lines.

33. A semiconductor memory according to claim 18, wherein said data line portions are formed of aluminum and said first word lines are formed of polysilicon.

34. A semiconductor memory according to claim 20, wherein each of said memory cells comprises a metal-oxide-semiconductor transistor, the respective output electrodes of two MOS transistors in two adjacent memory cells are connected at the same location to one data line portion, and the respective gate electrodes thereof are connected to two respective adjacent first word lines.

35. A semiconductor memory according to claim 34, wherein the direction of the channel formed between the source and drain regions of said MOS transistor is parallel to the direction of said data line portion.

36. A semiconductor memory according to claim 35, wherein said data line portion overlaps said channel as viewed in the vertical direction.

37. A semiconductor memory according to claim 34, wherein the gate electrode of said MOS transistor in each memory cell is formed by a portion of said first word line.

38. A semiconductor memory according to claim 34, further comprising

a pair of second word lines orthogonally crossing over said data line portions and being arranged at positions adjacent to each other;
 a first dummy memory cell coupled to one of the data line portions and one of said second word lines at the cross point thereof; and
 a second dummy memory cell coupled to the other of the data line portions of said pair of data line portions and the other of said second word lines at the cross point thereof.

39. A semiconductor memory according to claim 19, wherein said output signal deriving means comprises a pair of switching elements connected to said data line portions and a second differential amplifier connected to said pair of switching elements, to which the signals on said data line portions are selectively applied through said pair of switching elements, and the memory cells coupled to said data line portions are coupled in alternate pairs of adjacent word lines for each of said data line portions.

40. A semiconductor memory according to claim 19, wherein each of said memory cells is formed at a surface portion of a semiconductor body having one conductivity type and has a semiconductor region being formed in said surface portion and having the opposite conductivity type to said semiconductor body, said first word lines are formed on an insulator disposed on said body, and each of said data line portions has a first portion thereof being contact with said semiconductor region, and a second portion thereof insulated from both said body and said first word lines.

41. A semiconductor memory according to claim 26, wherein said output signal deriving means further comprises another differential amplifier connected to said pair of data lines, to which the signals on said data line portions are selectively applied through said pair of switching elements.

42. A semiconductor memory according to claim 26, wherein each of said switching elements comprises a MOS transistor having source and drain regions, and each of said pair of data line portions is connected through the channel formed between the source and drain regions of said transistor to each of said pair of data lines.
